UNITED STATES PATENT OFFICE.

ELIHU THOMSON, OF SWAMPSOFT, MASSACHUSETTS, ASSIGNOR TO THE AEOLIAN COMPANY, OF NEW YORK, N. Y., A COMPANY OF CONNECTICUT.

MUSIC-SHEET-GUIDING DEVICE.

No. 841,856.

Specification of Letters Patent.

Patented Jan. 15, 1907.

Application filed February 9, 1906. Serial No. 300,236.

To all whom it may concern:

Be it known that I, ELIHU THOMSON, a citizen of the United States, and a resident of Swampscott, county of Essex, Massachusetts, have invented certain new and useful Improvements in Music-Sheet-Guiding Devices, of which the following is a specification.

My invention relates to music-sheet-guiding devices such as are used in mechanical instrument-players and mechanical players for musical instruments. Such players are ordinarily controlled by a perforated music-sheet moving over the tracker.

The object of the present invention is to guide the sheet laterally during its longitudinal movement, so as to insure the exact registration of the perforations in the sheet with the corresponding ducts in the tracker, or, more broadly speaking, to insure such relative movement of the sheet and the tracker transversely of the path of the sheet as will secure their proper alignment. It is of course obvious that any considerable lateral deviation of the music-sheet would interfere with or destroy the proper rendition of the music.

A further object of the invention is to produce this lateral movement of the sheet by apparatus which acts to move the music-roll on which the sheet is originally wound and the winding-roll to which it is being wound simultaneously and equally.

Still further objects of the invention will appear in the specification and be pointed out in the claims.

In the drawings, Figure 1, partly in elevation, partly in longitudinally-vertical section, represents so much of a mechanical musical instrument as is necessary to illustrate my invention. Fig. 2 is a longitudinal section through the plane 2 2, Fig. 1. Figs. 3 and 4 are sections through the lines 3 3, Fig. 2, and 4 4, Fig. 1, the scale of these last figures being enlarged.

In the drawings, 1 designates a casing in which is mounted a tracker 2 and a music-sheet-winding roll 3. The casing 1 in the present illustration of my invention is made approximately air-tight and is connected with a source of pneumatic pressure. (Not shown.) Passing through the wall of the casing 1 is a shaft 4, on which the winding-roll 3 is mounted. Also passing through the wall

of the casing is a second shaft 5, having at its inner end, within the casing 1, a well-known clutch mechanism 6 for engaging with a co-operating clutch mechanism on the music-sheet roll 7, on which is wound the music-sheet 8, having perforations 9. The other end of the roll 7 is supported in a spring-supporting bearing 10, the shaft 11 of the roll having longitudinal motion in a recess 12 in the bearing. In like manner one end of the shaft 4 has longitudinal motion in a similar bearing 13 in a wall of the casing 1. Suitable means (not shown in the drawings) is provided for rotating the shafts 4 and 5 to unwind and rewind the music-sheet, 8 as required.

As a means for securing the proper lateral relation of the sheet 8 and the tracker 2, so that the perforations 9 in the sheet will correspond with the respective ducts in the tracker, I have shown mounted on the shafts 4 and 5, respectively, collars 14 15, with which engage pins 16, mounted on levers 17 18, the levers 17 18 being secured to a vertical shaft 19, as shown. A link 20 and connecting-rod 21 connect the shaft 19 with a finger 22 on a pneumatic bellows 23, pneumatically connected by a tube 24 to a pressure-chamber 25. A double valve 26, controlling a passage 27, leading from the chamber 25 to the atmosphere, permits the passage of air under pressure from the chamber 25 or atmospheric air alternately to the pneumatic 23. The valve 26 is connected, by means of a lever 28, to a diaphragm 29, which is in turn connected by a tube 30 to another pressure-chamber 31. In this chamber also is a double valve 32, adapted to admit alternately air under pressure from the chamber 31 or atmospheric air to pass through the tube 30. The valve 32 is connected to a diaphragm 33, the chamber of which has a small opening to the air or bleeder hole 45, and is connected by a tube 34 to a cylindric valve 35. (Clearly shown in Fig. 3 of the drawings.) The valve-chamber 35 is open at its end 36 to form a seat for a valve 37, normally held in seated position by a light spring 38. The valve 37 is connected by a cord 39 or the like to one end of a lever 40, pivoted at 41 to a stationary bracket 42, which is shown as secured to or directly in front of the tracker 2. At the free end of the lever 40 is a block 43, shown as bifurcate and as embracing the

edge of the music-sheet 8. Preferably the block 43 is pivoted at 44 to the lever 40.

The operation of the device is as follows: Assuming that the music-roll 7 has been

5 properly engaged between the bearing 10 and the shaft 5 and that the end of the sheet 8 has been connected with the winding-roll 3 and the apparatus put in motion, it is evident that the sheet will be drawn over the 10 tracker 2 to effect the playing of the instrument. It will be seen that the edge of the sheet passes between the bifurcate sides of the block 43. It will also be seen that the 15 pneumatic 23 tends by its expansion to force the music-sheet 8 to the left of the drawing Fig. 1, which tendency is opposed by the light spring 23^x. If at any time the sheet 8 should be forced too much to the left, its edge will bear against the block 43, so as to 20 turn the lever 40 on its pivot 41 and raise the valve 37 from its seat 36. Air under pressure from the chamber 1 will then pass through the valve-chamber 35 and tube 34 to raise the diaphragm 33 and move the valve 5 32 from the position shown in Fig. 1 of the drawings, so as to connect the tube 30 with the pressure-chamber 31. This in turn depresses the diaphragm 29 and acts, through the lever 28, to raise the valve 26. This cuts 30 off connection between the pressure-chamber 25 and pneumatic 23 and permits the pneumatic to exhaust to atmosphere. The spring 23^x then acts to draw the music-sheet 8 to the right of the drawing Fig. 1. It is 35 understood that in practice these lateral movements of the music-sheet 8 are very slight and are repeated as often as is necessary to insure movement of a music-sheet in its true path over the tracker 2. In ordinary 40 cases the alternate expansions and contractions of the pneumatic 23 will be very slight, amounting to a mere wavering of the finger 22 sufficient, however, to hold the music-sheet 8 in its correct alignment—that is, in 45 correct transverse relation to its path of movement.

It is obvious that very many mechanical changes may be made in the form of my invention without departing from its spirit.

50 It is also clear that while I have shown the instrument as actuated by pressure above that of atmosphere, it would require only such knowledge as is possessed by any one skilled in the art to make the necessary mechanical changes for adapting it to an instrument operated by suction.

What I claim is—

1. A music-sheet-guiding device comprising means normally operative to move the

sheet laterally in one direction, and means 60 including a part bearing against an edge of the sheet and movable laterally thereby for governing said sheet-moving means.

2. A music-sheet-guiding device comprising pneumatically-actuated means for moving the sheet laterally, a movable part against which the sheet bears when laterally deflected from its path, and connections between said movable part and said moving means for controlling the latter said connections including a pneumatic valve moved by said part.

3. A music-sheet-guiding device comprising means normally operative to move the sheet laterally in one direction, a movable 75 part against which the sheet bears when moved by said means from its path, and connections between said movable part and said sheet-moving means for controlling the latter.

4. A music-sheet-guiding device comprising means including an actuating-pneumatic and suitable connections for moving the sheet laterally, and means including a movable part against which the sheet bears when deflected from its path and a valve connected to said movable part, and pneumatic connections between said valve and said actuating-pneumatic for governing the latter.

5. A music-sheet-guiding device comprising a tracker, longitudinally-movable music-roll-supporting shafts at each side of said tracker, pneumatically-actuated means for longitudinally moving said shafts simultaneously and equally, a part bearing against 95 an edge of the music-sheet and movable laterally thereby, and a pneumatic valve moved by said part for governing said shaft-moving means.

6. A music-sheet-guiding device comprising a tracker, longitudinally-movable music-roll-supporting shafts at each side of said tracker, springs for pressing said shafts longitudinally in the same direction, pneumatically-actuated means for longitudinally moving said shafts simultaneously and equally against the action of said springs, and means including a part bearing against an edge of the music-sheet and movable laterally thereby for governing said shaft-moving means.

In testimony whereof I have signed this specification in the presence of two subscribing witnesses.

ELIHU THOMSON.
